ELECTRONIC DATA PRINTER

Philip H. Stevens, Syracuse, and David O. Chase, Camillus, N.Y., and Roger A. Schindler, Allison Park, Pa., assignors to SCM Corporation, New York, N.Y., a corporation of New York

Original design application Oct. 17, 1962, Ser. No. 72,137. Divided and this application June 18, 1964, Ser. No. 80,544

Term of patent 14 years

(Cl. D64—11)

Fig. 1

Fig. 2

Fig. 1

FIGURE 1 is a front perspective view of an electronic data printer showing our new design;

FIGURE 2 is a right side elevational view thereof; and FIGURE 3 is a top plan view thereof.

The back of the printer has a slight curvature and the two bottom inset flanges are continuous completely around the unit, the back of the printer being otherwise plain and unornamented.

The dominant features of our design are shown in full lines.

This application is a division of our copending application Serial No. D. 72,137, filed October 17, 1962, for a combined keyboard and electronic data printer.

We claim:

The ornamental design for an electronic data printer, substantially as shown and described.
